UNITED STATES PATENT OFFICE.

ISIDORE MARKS, OF BOSTON, MASSACHUSETTS, ASSIGNOR TO KEYSTONE MANUFACTURING COMPANY, OF BOSTON, MASSACHUSETTS, A CORPORATION OF MASSACHUSETTS.

DESIGN FOR A TOY MOTION-PICTURE MACHINE.

55,107.

Specification for Design.

Patented May 4, 1920.

Application filed October 17, 1919. Serial No. 331,483. Term of patent 7 years.

To all whom it may concern:

Be it known that I, ISIDORE MARKS, a citizen of the United States, residing at Dorchester, Boston, in the county of Suffolk and Commonwealth of Massachusetts, have invented a new, original, and ornamental Design for a Toy Motion-Picture Machine, of which the following is a specification, reference being had to the accompanying drawing, forming a part thereof,

The figure of the drawing is an exterior view, in perspective, of a toy motion picture machine showing my new design.

I claim:

The ornamental design for a toy motion picture machine substantially as shown.

ISIDORE MARKS.
